UNITED STATES PATENT OFFICE.

FRANK G. WILSON, OF GROVELAND STATION, NEW YORK.

METAL BURIAL RECEPTACLE.

Application filed September 15, 1921. Serial No. 500,819.

To all whom it may concern:

Be it known that I, FRANK G. WILSON, a citizen of the United States of America, residing at Groveland Station, in the county of Livingston and State of New York, have invented certain new and useful Improvements in Metal Burial Receptacles, of which the following is a specification.

The primary object of the invention is 10 the provision of a burial receptacle preferably formed of metal such as zinc coated steel, adapted for employment both as a casket and a shipping vault or box, the device possessing great strength and being 15 impervious to moisture.

A further object of the invention is the provision of a burial receptacle having a double top and being air and water tight as well as absolutely indestructible. The receptacle is easy to handle, possessing great 20 strength combined with lightness and is constructed without the use of bolts or rivets inside the receptacle. This burial receptacle is safe and sanitary and comparatively 25 inexpensive to manufacture while possessing a pleasant appearance and will remain undamaged by the weight of earth deposited upon the receptacle when buried in the ground.

With these general objects in view, the invention consists of the novel combination and arrangement of parts hereinafter more fully described in connection with the accompanying drawings and in which like 35 reference characters designate corresponding parts throughout the several views.

In the drawings.

Figure 1 is a side elevation of my receptacle in its closed position,

Figure 2 is a top plan view thereof,

Figure 3 is an enlarged central longitudinal sectional view taken upon the line III-III of Figure 2,

Figure 4 is a perspective view of an end 45 portion of the form of top employed with the receptacle as illustrated in Figures 1, 2, and 3,

Figure 5 is a top plan view of another form of top employed with the receptacle,

Figure 6 is a perspective view of an end portion of the top shown in Figure 5.

Figure 7 is a transverse sectional view thereof taken upon line VII-VII of Figure 5,

Figure 8 is a detailed horizontal sectional view taken upon line VIII-VIII of Figure

1 illustrating the corner construction of the receptacle, and

Figure 9 shows a different form of lid fastener that may be employed with the receptacle, portions of the latter being indicated by dotted lines.

Referring more in detail to the drawings, it will first be understood that my burial receptacle is preferably formed of sheet steel pressed into the shape desired, is then coated with zinc preferably by immersion and lastly is finished by suitable painting as well as lining in a manner that will be fully understood without further illustration.

The burial receptacle broadly comprises the box 10 with an inner lid 11 for closing the top thereof and a top 12 overlying the lid 11 as best illustrated in Figure 3 of the drawings.

The box 10 is rectangular in form having ends 13 and sides 14, being separate members joined together by overlapping beads or corner portions 15 and attached to a metal bottom 16 by marginal beads or overlapped portions 17. The sides and ends are formed of inner and outer layers of sheet metal 18 and 19 respectively and are bent into a groove or depression 20 spaced from the upper edge 21 of the box 10 and a similar groove 22 spaced from the bottom 16 thereof.

The sheet metal 18 and 19 is bent outwardly and inwardly in overlapping relations at substantially the center of the box 10 forming outwardly projecting ledges 23 upon the ends 13 and sides 14 of the receptacle. Suitable handles 24 are secured to the ledges 23 at any points desired and of any desired number, two handles 24 being herein illustrated upon the ledge 23 at the longitudinal side of the receptacle illustrated in Figure 1.

The outer metal layer 19 of the ends 13 and sides 14 is outwardly bent in L-shaped formation as at 25 forming a trough outwardly surrounding the upper edge of the box 10 with the outer side 26 of the trough 25 positioned above the level of the edge 21 of the box. A suitably formed lid 27 of rectangular form designed for positioning within the upper edge 21 of the box 10 has a marginal upstanding flange 28 adapted to overlie the box edge 21, transverse bracing ribs 29 being provided between the flanges 28. An outwardly projecting lip 30 upon the outer edge of the flange 28 provides

a substantially L-shaped member or extension outwardly of the box edge 21 within the surrounding channel or trough 25 of the box when the lid is in its closing position.

A suitable top 12 heretofore referred to comprises a plate 31 with transverse strengthening ribs 32 and an annular depending trough-shaped flange 33 positioned 10 in the trough 25 overlying the lip 30 and having a depending marginal apron 34 outwardly of the trough 25 when the top 12 is in its closed position, as illustrated in Figures 1 and 3. It will be seen that the lid 11 is readily placed in position and the top 12 mounted thereover while suitable cement or other plastic material 35 positioned in the trough 25 seals the joint between the trough 25 of the box 10, the lip 30 of the lid 11 and the flange 33 of the top 12. The receptacle may be either round, elliptical or square, as desired, and suitable securing hooks as 36 may be employed for the top 12 preferably overlying the latter and pivoted 25 at the lower ends beneath the trough 25. These securing means or fasteners are provided in any desired number suitably spaced apart around the top 12.

A different form of top 37 may be employed instead of the top 12 and this is provided with longitudinal side ribs 38 and a central rib or ridge 39 while a trough-shaped flange 40 surrounds the same in a depending manner similar to the trough 33 for reception in the trough 25 of the box 10. An outwardly spaced apron 41 upon the trough flange 40 corresponds to the apron 34 for positioning outwardly of the trough 25 when the top 37 is in its closing position. All of the joints in the device will be suitably brazed and the structure being pressed from sheet steel is designed for coating inside and outside with zinc preferably by the dipping process. The receptacle may be finished by suitable painting if desired and then lined with cloth or otherwise as found desirable. The handles being secured to the ledges 23 and all of the joints being in the form of brazed beading, there are no bolt or rivet portions projecting within the receptacle.

The grooves 20 and 22 in the sides and ends of the box 10 may be fitted with wooden strips if found desirable for ornamentation 55 or for the purpose of attaching cloth or other covering to the box 10. This form of receptacle eliminates separate corner members such as those commonly employed and insures great strength with either round, 30 elliptical or square ends. The fasteners 36 secure both the lid and top members in locked position for closing the box 10. While the form of the invention herein set

forth is believed preferable, it will be understood that minor changes may be made therein without departing from the spirit and scope of the invention. 65

The lid fastener shown in Fig. 9 includes a plate 40' carried by the marginal portion 12 of the casket, a lever 41' being hinged as 70 at 42 to the plate 40' and having a resilient hook 43 hinged at 44 to the lever 41'. The lower free end 45 of the hook 43 is adapted to engage beneath the overhanging trough portion 25 of the receptacle and whereby 75 the movement of the handle 41' is adapted to lock and release the hook 43 in either position desired.

What is claimed as new is:

1. A burial receptacle comprising a box 80 having an upper edge, a marginal trough surrounding the upper edge of the box, a sheet metal lid having an upstanding marginal flange adapted for overlying said edge when the lid is positioned in the open top 85 of the box, an outwardly projecting lip upon said flange positioned within the trough when the box is closed and transverse ribs carried by the lid between the flanges at the sides of the lid. 90

2. A burial receptacle comprising a box having an upper edge, a marginal trough surrounding the upper edge of the box, a sheet metal lid having an upstanding marginal flange adapted for overlying said edge 95 when the lid is positioned in the open top of the box, an outwardly projecting lip upon said flange positioned within the trough when the box is closed, transverse ribs carried by the lid between the flanges 100 at the sides of the lid, a top for overlying the lid, a depending trough-shaped flange upon the top adapted for positioning within the trough of the box when the device is assembled, an outer apron upon the trough-shaped flange of the top positioned outwardly of the box trough when assembled and transverse strengthening ribs upon said top spaced from the outer wall of the trough-shaped flange of the top. 110

3. A burial receptacle formed of pressed sheet steel including a box member, a trough-shaped flange surrounding the top of the box member, an inner lid seated within the top of the box overlying the upper edge 115 thereof and seated within the trough-shaped flange when the device is closed, a top member overlying the lid projecting within said trough-shaped flange and having a downwardly projecting portion outwardly of said flange and hermetically sealing means within the trough-shaped flange contacting the enclosing portions of the lid and top. 120

In testimony whereof I affix my signature.

FRANK G. WILSON.
